UNITED STATES PATENT OFFICE

2,388,345

STEAM GENERATOR

Glen Anderson Skaggs, Portsmouth, Va.

Application April 20 1944, Serial No. 531,931

4 Claims. (Cl. 122—41)

The present invention relates to new and useful improvements in power plants and more particularly to a steam driven turbine and has for its primary object to provide a pulsating steam generator whereby the water supply has no direct connection with the steam generating chamber and steam cannot escape into the delivery pipe until the pressure has built up sufficiently for operating the turbine.

In carrying out this object I provide a pressure responsive valve having spring means for normally maintaining the valve in closed position and arranged to open when a predetermined steam pressure is generated to then feed the steam to the turbine.

A further important object of the invention is to provide automatically controlled water supply means for the steam chamber which is also regulated by the aforesaid valve.

A still further object is to provide a steam generator of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a side elevational view with parts broken away and shown in section, and

Figure 2 is a sectional view taken substantially on a line 2—2 of Figure 1.

Referring now to the drawing in detail, wherein for the purpose of illustration I have disclosed a preferred embodiment of my invention, the numeral 5 designates a turbine housing supported on a suitable base 6 by means of legs or the like 7 and rotatably mounted in the housing is a turbine wheel 8 of conventional construction, such as indicated in Patent No. 1,654,889, dated January 3, 1928. The shaft on which the turbine wheel is rotatably mounted is indicated at 9.

Secured to one side of the casing 5 are brackets 10 on which a water tank or reservoir 11 is supported and also secured to one of the brackets 10 is a steam chamber 12, the chamber preferably being of elongated form arranged in a horizontal position and supported at one end by a leg 13.

Suitably secured in the chamber 12 and spaced from the longitudinal walls thereof is a cylinder 14 having a cylindrical valve housing 15 extending from one end thereof. The cylinder 14 has a

piston 16 working therein and the piston rod 17 constitutes a valve working in the valve housing 15. Also positioned in the valve housing 15 behind the valve 17 is a coil spring 18 adapted to urge the piston toward an opposite end of the cylinder 14 short of closing a port 19 communicating with the steam chamber 12. The tension of the spring 18 is adjusted by means of a screw 20 threaded through the adjacent end of the valve chamber. The piston 16 has a stop member 16' extending axially from its end for limiting the movement thereof by the spring 18 to prevent the piston from closing the port 19. That is to say, the member 16' comes in contact with the end of the cylinder 14 so as to prevent the piston 16 from closing the port 19.

A priming cup 21 is also secured to the side of the casing 5 and has a pipe 22 feeding from the bottom thereof through the top of the steam chamber 12 and also through the top of the valve housing 15 for communication with a groove 23 formed in the valve 17. A short pipe 24 extends downwardly from the valve housing 15 in vertical alignment with the pipe 22, the lower end of the pipe 24 terminating above a cup or recess 25 formed in the bottom of the steam chamber 12. Immediately below the cup 25 is a lamp, burner or other heating element 26.

A horizontal partition 27 is placed in the priming cup 21 having vent openings 28 therein normally closed by a valve 29 positioned against the under side of the partition 27 and held in a closed position by a coil spring 30 engaging the head 31 formed on the upper end of the stem 32 extending from the valve 29 upwardly and slidably through the partition. Obviously, water may be placed in the priming cup 21 through the open top thereof, and allowed to drain through the vent openings 28 of the partition 27 to the bottom of the cup, by manually opening the valve 29, and while the valve 29 is held open the vent openings 28 assure the flow of water into the pipe 22, but after starting operation of the steam generator the spring influenced valve 28 keeps the vents 28 closed.

A second annular groove 33 is formed in the valve 17 and adapted upon a predetermined movement of the valve to register with a port 34 formed in the bottom of the valve housing 15 and a pipe 35 leading from the top of the valve housing 15 into a jet passage 36 communicating through a side of the casing 5 with the turbine wheel 8. The port 34 in the valve housing 15 communicates with the steam chamber so as to admit steam from the chamber to the turbine wheel by way of the groove

33 in the valve 17 when said groove is in registry with the port 34 and pipe 35.

A feed pipe 37 extends from the bottom of the tank 11 to the bottom portion of the valve housing 15 and a stand pipe 38 extends from the top of the valve housing 15 in vertical alignment with the pipe 37, the pipe 38 extending upwardly and communicating with the tank 11 above the level of the water 39 therein.

In the operation of the device, the piston 16 and valve 17 is normally held in the position shown in Figure 1 of the drawing by the spring 18 and prior to the generation of steam in the chamber 12, whereby the groove 23 in the valve 17 will provide communication between the pipes 22 and 24. By manually opening the valve 29 the vent 28 will be opened whereby to permit water from the priming cup 21 to pass through the pipes 22 and 24 into the steam generating cup 25.

At the same time the groove 33 will be out of registry with the port 34 and pipe 35, and accordingly when heat is applied to the water in the steam generating cup 25 the steam will be collected in the chamber 12 and enter the port 19 behind the piston 16. When a predetermined pressure of steam has been generated the piston 16 will be moved toward the right against the tension of the spring 18 whereby to move the groove 23 out of registry with the pipes 22 and 24 to close communication with the priming cup and to move the groove 33 into registry with the port 34 and pipe 35 to permit passage of the steam from the steam chamber 12 to the jet passage 36 for operating the turbine wheel 8. At the same time the groove 23 in the valve stem 17 will be moved into registry with the pipes 37 and 38 whereby to supply the groove 23 with water. Accordingly when the pressure of the steam has been lowered through its consumption in operating the turbine, the spring 18 will move the piston 16 and valve 17 toward the left to again bring the groove 23 into registry with the pipes 22 and 24 and the water which has been collected in the groove 23 will then be deposited into the steam generating cup 25 and the groove 33 will be moved out of registry with the port 34 and pipe 35 whereby steam will again be generated in the chamber 12 for repeating the operation.

A vent opening 40 is formed in the lower portion of the pipe 22 to facilitate discharge of the water from the groove 23 into the steam generating cup.

Any number of devices forming the subject matter of this invention as heretofore described in detail may be provided on the turbines for the actuation of the rotors thereof.

It is believed the details of construction, operation and advantages of the device will be readily understood from the foregoing without further detailed explanation.

Having thus described the invention, what I claim is:

1. A steam generator of the kind described comprising a steam generating chamber, a valve casing in the chamber, a steam feed passage leading from the chamber through the casing to the utility to be supplied with steam, a water supply pipe communicating with the casing, a water discharge pipe leading from the casing to the chamber, a steam pressure responsive piston having a cylindrical valve connected thereto and working in the valve casing, said valve having spaced circumferential grooves therein, one of said grooves

being adapted to register with the steam passage to open and close communication therethrough and the other groove being adapted to alternately register with the water feed and discharge pipes to periodically supply water to the steam generating chamber, and spring means normally urging the valve in one direction against the action of the steam pressure but yielding to movement of the valve in the opposite direction under pressure of steam generated in said generating chamber.

2. A steam generator of the kind described comprising a steam generating chamber, a steam feed passage leading from the chamber to the utility to be supplied with steam, a water feed passage communicating with the chamber, an encased reciprocatory steam pressure responsive valve having spaced circumferential grooves therein and adapted to register respectively with the steam and water passages to alternately open and close communication therethrough to said steam generating chamber, and a manually operated priming cup communicating with the steam generating chamber through one of said valve grooves to supply water to said chamber for starting generation of steam therein.

3. A steam generator of the kind described comprising a steam generating chamber, a steam feed passage leading from the chamber to the utility to be supplied with steam, a water feed passage communicating with the chamber, an encased reciprocatory steam pressure responsive valve having spaced circumferential grooves therein and adapted to register respectively with the steam and water passages to alternately open and close communication therethrough to said steam generating chamber, a manually operated priming cup communicating with the steam generating chamber through one of said valve grooves to supply water to said chamber for starting generation of steam therein, and spring means urging the valve into a position with the priming cup in feeding position but yielding to movement of said valve in the opposite direction under pressure of steam generated in said generating chamber.

4. A steam generator of the kind described comprising a steam generating chamber, a cylinder arranged in said chamber and having an elongated cylindrical valve casing at one end, said cylinder having communication with the generating chamber at its other end, a piston working in said valve cylinder, an elongated valve connected to the piston and working in the valve casing, said valve having longitudinally spaced circumferential grooves therein, a steam passage leading from the chamber through the valve casing to the utility to be supplied with steam and with which steam passage one of the grooves of said valves is registerable, a water supply pipe leading to the valve casing and a water discharge port in the valve casing communicating with the steam chamber and adapted for alternate registry with another of said valve grooves, a priming supply pipe leading to the valve casing in alignment with the discharge port, and spring means urging the valve into a position for registering said last named groove with said priming supply pipe and the discharge port, said piston being responsive to a predetermined steam pressure generated in the chamber to close the discharge port and open the steam feed passage.
